No 856.

Inv. T. Dury^s
Design for Cook Stove.

Patented Dec. 23, 1856.

Des. 856

John T. Dury, of Troy, N.Y.
Letters Patent No. 856. Dated Dec 23rd 1856.

The Schedule referred to in these Letters Patent and
making part of the same.

To all whom it may concern:

Be it known that I, pro.
P. Davy of Troy in the county of Rensselaer and
State of New York, have invented or produced a
new and original design for a cook stove, which
I call the "Hercules" and I do hereby declare that
the following is a full, clear and exact description
of the same, reference being had to the annexed
perspective drawing, and the letters of reference
marked thereon, forming part of this specifica-
tion.

The description of my new stove design is as
follows, viz: A is the top plate, having an or-
namental moulding (a) around its edges. B is
the jamb plate, with moulding (b.b). C & D are
the oven doors with the ornamental moulding (c.c)
and rosettes (d.d) upon the panels. E is the end
fire door, having the ornamental moulding (e.e)
and rosette (f) upon the panel. F is the front upper
plate, and G.G are the front fire doors, with or-
namental mouldings (g.g) and rosettes (h.h) upon
their panels. H is the hearth, having the ornamen-
tal moulding (i.i) for its border. I is the lower front
plate, ornamented with the moulding (j) and panel
ornament (k). L is the bottom plate, with ornamen-
tal moulding (m). K is the leg ornamented with
the shell (n) and scrolls (o) upon its face.

Having fully described my
design for cook stove. What I claim as new
therin and desire to secure by letters patent
is: The ornamental configuration and design
for cook stove plates, such as herein described
